G. W. BULLEY

SOUND AMPLIFYING HORN

Filed June 29, 1926

Inventor:

George W. Bulley,
by Spear, Middleton Donaeson, Hale
Atlys.

UNITED STATES PATENT OFFICE.

GEORGE W. BULLEY, OF AKRON, OHIO, ASSIGNOR TO THE MILLER RUBBER COMPANY,
OF AKRON, OHIO, A CORPORATION OF OHIO.

SOUND-AMPLIFYING HORN.

Application filed June 29, 1926. Serial No. 119,328.

My present invention relates to improvements in sound amplifying horns and aims to provide a horn which will have a maximum length of sound amplifying space with a minimum of exterior dimensions, and the invention includes the novel construction hereinafter described and defined by the appended claims.

An embodiment of the invention is illustrated in the accompanying drawings in which:—

Fig. 1 is a side elevation of such a horn.

Fig. 2 is a plan view, and Fig. 3 an end view.

15 Referring by reference characters to this drawing the numeral 1 designates the bell member which is formed of what may be termed cup shape, preferably of approximately semi-circular form as viewed in side 20 elevation (Fig. 1), but with a flattened circumferential wall 1^a and flattened sides 1^b flaring laterally at 1^c . 2 designates a neck member which is elongated and tapered and formed into almost a complete circle the exterior diameter of which at its widest point corresponds to the interior diameter of the bell member.

The neck member is inserted in the bell member as shown in Fig. 1 so that its ends 30 are within the bell member while the intermediate looped portion projects from the mouth of the bell.

The smaller end of the neck member is curved and passed through the bottom wall 35 of the bell where it is secured by means such as lock nut 1^d . The larger end of the neck member may be secured to the wall of the bell by means such as bolt 1^e .

The neck member is preferably made of 40 approximately rectangular shape in cross

section, except its smaller end, so as to provide a flat outer circumferential wall to lie in juxtaposition and fit snugly against the inner circumferential wall of the bell member.

45 I have found that an amplifying horn such as described may be easily made of hard rubber as the bell member may be easily molded from such material by the usual molding processes, while the neck member may be 50 formed by a blowing method such for example as that used in forming the neck of the horn described in Patent 1,536,700 of May 5, 1925.

I have further found that such a horn 55 produces very satisfactory results as to sound amplification.

I claim:

1. A sound amplifying horn comprising a substantially cup shaped bell member and an elongated curved neck member having one end passing through an opening in the wall of the bell member and secured thereto and its other end within and secured to the wall of the bell portion and having its open end directed towards the bottom of the bell member.

60 2. A sound amplifying horn comprising a bell member having a closed inner end and a substantially semi-circular circumferential wall and an elongated curved tapered neck member having end portions lying substantially within the bell member and an intermediate loop projecting from the mouth of the bell, said neck member having its smaller 70 end projected through an opening in the wall of the bell member.

75 In testimony whereof, I affix my signature.

GEORGE W. BULLEY.
